DESIGN FOR A DISPLAY STAND

Paul M. Ressinger, Chicago, Ill.

Application April 23, 1947, Serial No. 138,561

Term of patent 7 years

(Cl. D80—9)

To all whom it may concern:

Be it known that I, Paul M. Ressinger, a citizen of the United States, residing at Chicago, in the county of Cook and State of Illinois, have invented a new, original, and ornamental Design for a Display Stand, of which the following is a specification, reference being had to the accompanying drawing, forming part hereof:

Figure 1 is a perspective view of a display stand, showing my design;

Figure 2 is an end elevation; and

Figure 3 is a perspective view thereof on a reduced scale, showing the opposite side of Figure 1.

I claim:

The ornamental design for a display stand, as shown.

PAUL M. RESSINGER.
